UNITED STATES PATENT OFFICE.

ADOLPHUS S. RAGER, OF FREDERICK, MARYLAND.

COMBINED PIPE-HOLDER AND PIPE-VISE.

SPECIFICATION forming part of Letters Patent No. 486,124, dated November 15, 1892.

Application filed June 14, 1892. Serial No. 436,659. (No model.)

To all whom it may concern:

Be it known that I, ADOLPHUS S. RAGER, a citizen of the United States, residing at Frederick, in the county of Frederick, State of Maryland, have invented certain new and useful Improvements in a Combined Pipe-Holder and Pipe-Vise, of which the following is a specification, reference being had therein to the accompanying drawings.

10 The objects of my improvement are to produce a simple and inexpensive machine adapted for use over wells to retain a pipe while it is raised or lowered during the setting of a pump or of a pump-rod. The machine is also adapted for use as a pipe-vise to strongly 15 clutch a pipe while screw-threads are cut upon its ends or upon any other part of its length. I attain these objects by the construction illustrated in the accompanying drawings, in 20 which—

Figure 1 is a perspective view of a pipe-holder constructed in accordance with my invention. Fig. 2 is a transverse vertical section on line $x x$ of Fig. 3. Fig. 3 is a longitudinal vertical section on line $y y$ of Fig. 2. Fig. 4 is a perspective view of the movable jaw of the combined pipe-holder and pipe-vise.

25 In said drawings, A represents the base-plate, which may be of wood or metal, upon which is placed the stationary jaw B, secured to the base-plate by means of two vertical bolts b. Said jaw is also received within an inclosing metal frame A², that is secured to the base-plate. The sides of the frame A² have slots a² made horizontally therein to 30 guide the ends d of the head-block D of a carriage carrying the crescent-shaped blade E, used to clamp vertically between it and the stationary jaw B any pipe or rod that may 35 be placed between said blade and jaw. Upon the cylindrical ends d of the head-block are mounted the outer ends of the sides D² of the carriage, and the inner ends of said sides have 40 horizontal grooves therein to receive the tenons e, projecting from the ends of the blade E. The sides D² of the carriage normally rest upon the base-plate A and are guided either 45 by the edges of a plate a, secured on top of a base-plate A, or by the slotted sides of the frame A², or by both of these parts, as shown,

the nuts d² upon the screw-threaded ends d of the head-block serving, also, to keep the carriage in alignment with the face of the stationary jaw. To move the blade-carrying 55 or jaw-carrying carriage back or forth in its guideways, a screw F is made to pass through a screw-threaded hole in one end of the frame A². Said screw has on its outer end a hand-wheel G, by which it can be rotated, and its 60 inner end is shouldered or reduced in diameter and received loosely in a horizontal perforation in the center of a head-block D. The end of the screw beyond the front of said block is provided with a nut or head to retain 65 it permanently united but loosely fitted in the head-block.

Although the front of the carriage and its blade E can be tipped up, as shown by dotted lines in Fig. 3, the head-block D of said carriage remains resting upon the guide-plate a and the screw F remains in a horizontal position. The hinging of the carriage substantially upon the end of the screw permits said carriage or its front blade to drop into 70 engagement with any-sized pipe or rod that may be placed against the stationary jaw, and the screw permits any desired adjustment to be made.

When the device is to be used as a pipe-vise, the blade E is removed from the carriage and the jaw H is substituted, its tenons e being received in the horizontal grooves formed in the front ends of the sides D² of the carriage. Said jaw H has a large V-shaped 80 groove H² in its front, and said groove has in its face a series of angular teeth h², as usual. This jaw is of suitable size to enter in a chamber K kept for it under the stationary jaw B, a triangular block B² being located under the jaw B, adapted to be received in the 85 V-shaped groove H² of the movable jaw H. 90

Having now fully described my invention, I claim—

1. In combination with the base-block and 95 stationary jaw of a pipe-holder, the frame inclosing said jaw, a hand-screw retained parallel with the base-block, a head-block loosely mounted upon one end of said screw and forming the rear end of a carriage, the sides 100 of said carriage pivoted to the head-block, a blade removably secured to said sides, and a

plate secured to the base-block between the sides of the carriage, whereby the latter is guided, substantially as described.

2. In combination with the base-block and stationary jaw of a pipe-holder, the frame inclosing said jaw and having slots in its sides, a hand-screw retained parallel with the base-block, a head-block loosely mounted upon one end of said screw and having its ends received in guide-slots of the frame, the sides

of a blade-carrying carriage pivoted to the head-block, and a blade rearwardly secured to said sides, substantially as described.

In testimony whereof I affix my signature in presence of two witnesses.

ADOLPHUS S. RAGER.
